United States Patent Office

Des. 178,656
Patented Sept. 4, 1956

178,656

SOFA BED UNIT

Louis Elliott Frey, Los Angeles, Calif.

Application October 24, 1955, Serial No. 38,533

Term of patent 14 years

(Cl. D5—4)

FIG. 1.

FIG. 2.

FIG. 3.

FIG. 4.

Fig. 1 is a perspective view of a sofa bed unit in closed position, showing my new design;

Fig. 2 is a perspective view showing the same in open position;

Fig. 3 is an elevational view taken along the side of the bed substantially opposite from Fig. 1; and

Fig. 4 is an elevational view taken from the rear of the head of the bed.

I claim:

The ornamental design for a sofa bed unit, substantially as shown and described.
